UNITED STATES PATENT OFFICE.

JOHN HORMBY, OF SPRINGFIELD, MASSACHUSETTS.

TURBINE.

No. 927,536.

Specification of Letters Patent.

Patented July 13, 1909.

Application filed June 19, 1908, Serial No. 439,287. Renewed April 7, 1909. Serial No. 488,488.

To all whom it may concern:

Be it known that I, JOHN HORMBY, a citizen of the United States, and a resident of Springfield, in the county of Hampden and State of Massachusetts, have invented certain new and useful Improvements in Turbine-Motors, of which the following is a specification.

My invention relates to motors of the turbine type and its novelty consists in the construction and adaptation of the parts as will be more fully hereinafter pointed out.

In a co-pending application for Letters Patent of the United States, Serial No. 439,285 filed by me on the 19th day of June, 1908, I have described a peculiar form of jet propelled vane or bucket which I call for the sake of identification a "demi-vane" and which, in brief, is made integral with the disk 20 on which it is mounted and comprises a crescent-shaped body with cylindrical surfaces oblique to its supporting disk and to the shaft on which it is rotated. The subject matter of this invention is a result of the further development or carrying forward of the inventive ideas described in that application. Necessarily in the description which follows I must repeat something of the descriptive matter of that application.

Figure 1 is a longitudinal vertical section and partial front elevation of a device embodying my invention and Fig. 2 is a transverse vertical section through the casing on the plane of the line 2—2 in Fig. 1 and a side elevation looking from right to left in that figure.

In the drawings, 20 is a casing adapted to contain a double turbine comprising disks 11, 12 and 13, all secured to a shaft 10 adapted 40 to rotate in suitable bearings in the side of the casing. Each disk 11 and 13 is imperforate on its outer surface and each has an inwardly projecting peripheral rim provided with the demi-vanes above referred to. The adjacent disk 12 has a central web and two outwardly projecting peripheral rims each provided with demi-vanes as described in the patent application above referred to but with this important difference. The adjacent vanes on the disks 11 and 12 and the adjacent vanes on the disk 12 and 13 all are adapted to receive steam from the same direction and to rotate in the same direction. In other words, the three disks together constitute a composite double turbine with two series of propelling vanes, which, for the sake

of brevity, I will call *a* and *b*. The demi-vanes on the opposing faces of the adjacent disks preferably are staggered to prevent any tendency to side thrust. This arrangement 60 is not necessary but is quite convenient.

The casing 20 is provided with two nozzles, one 21 leading to the vane series *a*, and the other 22 leading to the vane series *b*. These lead from a chamber 230 in a steam chest 23 supplied with steam from a suitable conduit indicated at 24. The steam chest is divided into a plurality of compartments 230 just mentioned, 231, and 232, separated from each other by strong steam tight partitions 70 233.

There are additional casings 200 and 201, each containing a composite turbine made up of vaned disks 11, 12 and 13 and each constructed and operated in the same manner. 75

A cross over port 234 leads from the casing 20 to the compartment 231 and a similar cross over port 235 of larger cross sectional area leads from the casing 200 to the compartment 232.

Steam nozzles 236 and 237, each of larger cross sectional area than the nozzles 21 and 22, lead from the compartment 231 to the vane series *a* and *b* of the composite turbine in the casing 200 and similar steam nozzles 85 238 and 239, larger in cross sectional area than the nozzles 236 and 237, lead from the compartment 232 to the vane series *a* and *b* of the composite turbine in the casing 201. The shaft from the last mentioned composite 90 motor is connected by proper power transmitting mechanism indicated at 40 to any place where the developed energy may suitably be employed. A final discharge conduit 240 leads from the casing 201. 95

In operating the device, steam from the compartment 230 is admitted to the nozzles 21 and 22 and impinging upon the vane series *a* and *b* of the composite motor in the casing 20 energizes the motor and passes out through the spaces between the vanes or through appropriate apertures in the disks 11, 12 and 13 provided for the purpose into the space within the casing 20. Thence the steam passes through the cross over port 234 to the 100 compartment 231 and into the nozzles 236 and 237 leading to the next composite motor. It will be noted that while the cross sectional area of each nozzle 236 and 237 is greater than that of the nozzles 21 and 22 yet the 110 vanes on the motor supplied therefrom are no larger and no more numerous. After be-

2
ing discharged from this motor into the casing 200 the steam passes through the cross over port 235 into the compartment 232 and thence into the nozzles 238 and 239 which 5 are larger in cross sectional area than the nozzles 236 and 237, while the size of the vanes on the motor supplied therefrom is no larger and the vanes are no more numerous than before. The steam discharged from the 10 last mentioned motor into the casing 201 passes out through the port 240.

By this construction I am enabled to use motor turbines having vanes of the same size and number while I compound the steam and 15 expand it from one steam chest to the other enlarging the cross sectional area of the successive cross over ports and energizing nozzles only. This means uniformity of design and simplicity in construction of the different turbines and economy in manufacture 20 and practice.

What I claim as new is:

1. In a compound steam turbine, the combination of a plurality of sets of turbines, each 25 set comprising turbine disks having demivanes projecting inwardly at an angle therefrom in opposing relation, a steam inlet for the propelling jet of one of said sets, and means to supply steam in a relatively increasing volume to each succeeding set, from the exhaust 30 of the preceding set.

2. In a compound steam turbine, the combination of a plurality of sets of turbines

mounted upon a common shaft, each set comprising three turbine disks, the two outer disks 35 having a series of inwardly projecting vanes, and the inner disk having two series of outwardly projecting vanes, forming double turbines, a steam inlet for the propelling jet of one of said turbine sets, and means to supply 40 steam in a relatively increasing volume to each succeeding set, from the exhaust of the preceding set.

3. In a compound steam turbine, the combination of a plurality of separated sets of 45 turbines mounted upon a common shaft, each set comprising three turbine disks, the two outer disks having a series of inwardly projecting vanes, and the inner disk having two 50 series of outwardly projecting vanes, extending at an angle to their respective disks and toward one another in pairs, a steam inlet for one of said turbine sets, means connecting the said sets to supply steam in a relatively increasing volume to each succeeding set, 55 from the exhaust of the preceding set, and nozzles for the vane series of each of said sets, of varying area to correspond to the volume of the steam supply thereof.

Witness my hand this 17th day of June 60 1908, at the city of New York, in the county and State of New York.

JOHN HORMBY.
